(57) **CLAIM**

The ornamental design for a kitchen storage rack, as shown and described.

DESCRIPTION

FIG. 1 is a top, front, left-side, perspective view of a kitchen storage rack;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

In the drawings, the broken lines are for the purpose of illustrating portions of the kitchen storage rack that form no part of the claimed design.

1 Claim, 3 Drawing Sheets
